Application June 15, 1956, Serial No. 41,910

Term of patent 14 years

(Cl. D58—25)

Fig. 1.

Fig. 3.

Fig. 2.

Fig. 4.

Figure 1 is a side elevational view of a jar or similar article embodying my new design.

The broken line showing of the cap portion is for illustrative purposes only.

A characteristic feature of my design for the jar disclosed resides in the base portion having the configuration shown.

I claim:

The ornamental design for a jar or similar article, substantially as shown and described.
